John E. Earle.

United States Patent Office.

MERWIN FOWLER, OF WOLCOTTVILLE, CONNECTICUT.

Letters Patent No. 82,821, dated October 6, 1868.

IMPROVED BUCKLE.

The Schedule referred to in these Letters Patent and making part of the same.

TO ALL WHOM IT MAY CONCERN:

Be it known that I, MERWIN FOWLER, of Wolcottville, in the county of Litchfield, and State of Connecticut, have invented a new Improvement in Buckles; and I do hereby declare the following, when taken in connection with the accompanying drawing, and the letters of reference marked thereon, to be a full, clear, and exact description of the same, and which said drawing constitutes part of this specification, and represents a perspective view.

The invention relates to an improvement in that class of buckles commonly used for wearing-apparel, formed in two parts, the frame being one of the parts, and the loop and tongue combined forming the second part; and the invention consists in the attachment of the tongues and loop to the frame, by bending the wire of which the tongue and loop are composed around the ends of the frame, and turned up against the ends of the frame, so as to hold the parts in their proper position, hinged together.

In order to the clear understanding of my invention, I will fully describe the same as illustrated in the accompanying drawings.

A is the frame, formed in any convenient manner, its two ends, *a* and *b*, turned down, so as to leave a space between the two ends, equal to the spread of the tongues from outside to outside. B is the loop; C C, the two tongues, both tongues and bar formed from one and the same piece of wire, and hinged to the frame by bending over the ends of the frame, and down, so that a loop, *d*, is formed around each end of the frame, then turned up, so that each tongue passes the end of the frame, and thus prevents the loop from slipping laterally on the frame.

Having thus fully described my invention, what I claim as new and useful, and desire to secure by Letters Patent, is—

A buckle, consisting of the frame A, the loop B, and tongues C C, the said loop and tongues being formed in one piece, and hinged to the frame, so as to be retained in their proper relative position, substantially as herein set forth.
